CLAIM

We claim, the ornamental design for a detonator, as shown and described.

DESCRIPTION

FIG. 1 is a perspective view of a detonator according to the new design;

FIG. 2 is a plan view of the detonator of FIG. 1;
FIG. 3 a view of a first end of the detonator of FIG. 1; and,
FIG. 4 is a view from an opposing second end of the detonator of FIG. 1.
